His Attorney.

UNITED STATES PATENT OFFICE

MORRIS TREIMAN, OF ST. LOUIS, MISSOURI, ASSIGNOR TO MEXICAN AMERICAN HAT COMPANY, OF ST. LOUIS, MISSOURI, A CORPORATION OF MISSOURI

DESIGN FOR A HAT

Application filed September 10, 1928. Serial No. 28,090. Term of patent 7 years.

To all whom it may concern:

Be it known that I, MORRIS TREIMAN, a citizen of the United States, and residing at St. Louis, Missouri, have invented the new, original, and ornamental Design for a Hat, of which the following is a specification, reference being had to the accompanying drawing, forming a part thereof.

The figure is a perspective view of a hat showing the new design.

The characteristic feature of the design resides in the embodiment of a figure of an airplane across the center of the crown and merging into a rib extending from the crown and from the rim of the hat medially along the line of flight of the airplane.

I claim:

The ornamental design for a hat as shown and described.

In testimony whereof, I affix my signature this 23d day of July, 1928.

MORRIS TREIMAN.
